United States Patent Office

Des. 196,059
Patented Aug. 20, 1963

196,059

PLATE OR SIMILAR ARTICLE

Tony Jack Edwards, Petaluma, Calif., assignor to Technical Porcelain and Chinaware Co., El Cerrito, Calif., a partnership

Filed Mar. 12, 1963, Ser. No. 73,939

Term of patent 14 years

(Cl. D44—15)

The FIGURE of the drawing is a plan view of a plate or similar article of conventional configuration showing my new design.

The decoration shown is repeated around the circumference of the plate.

I claim:

The ornamental design for a plate or similar article, substantially as shown and described.
